CIRCUIT BREAKER

James F. Raleigh, River Forest, Ill., assignor to
 Underwood Electric & Mfg. Co., Inc., Chicago,
 Ill., a corporation of Illinois

Application March 12, 1948, Serial No. 14,467

8 Claims. (Cl. 200—113)

1

My invention is concerned with improvements in bi-metallic reed circuit breakers.

An object of my invention is to provide bi-metallic reed circuit breakers which in many instances are preferable to fuses for the protection of electrical circuits against overloads.

Another object of my invention is to provide bi-metallic reed circuit breakers of simple, compact and sturdy construction which are dependable and effective in operation and capable of being manufactured with uniformity and economy.

Another object of my invention is to provide a dependable and effective bi-metallic reed circuit breaker so constructed that it is both compact and wafer-like and capable of being mounted in space-conserving relationship with similar circuit breakers on a panel board or like support.

Another object of my invention is to provide the housing of a bi-metallic reed circuit breaker with an interiorly located reed-supporting stud that is readily adjustable with a tool applied exteriorly of the housing, or housing part with which the reed is associated, to effect adjustments of the reed and its contact relatively to a co-operating contact.

The aforementioned and other objects and features and advantages of my invention are discussed in the description to follow wherein reference is made to the accompanying drawings in which:

Fig. 1 is an elevational view of one side of a circuit breaker embodying my invention;

Fig. 2 is a similar view of the other side thereof;

Fig. 3 is a top plan view thereof;

Fig. 4 is a bottom plan view thereof;

Fig. 5 is an elevational view of one end thereof;

Fig. 6 is an elevational view of the inner face of the reed-carrying component of the circuit breaker housing as such component appears before application thereto of the reed;

Fig. 7 is a view, similar to Fig. 6 and of the same component of the housing, as said component appears after application thereto of the reed;

Fig. 8 is an elevational view of the inner face of the stationary-contact-carrying component of the housing as such component appears after application thereto of the stationary contact;

Fig. 9 is an isolated side elevational view of the insulator component of the housing;

Fig. 10 is a sectional view which may be regarded as taken on the line 10—10 of Fig. 1 and looking in the direction indicated by the arrows;

2

Fig. 11 is a sectional view which may be regarded as taken on the line 11—11 of Fig. 2 and looking in the direction indicated by the arrows;

Fig. 12 is a sectional view which may be regarded as taken on the line 12—12 of Fig. 1 and looking in the direction indicated by the arrows;

Fig. 13 is a view largely in end elevation and partly in section illustrating how a multiplicity of my novel circuit breakers are adapted to be mounted with economy of space on a common panel board;

Fig. 14 is a side elevational view depicting how a modified form of my novel circuit breaker may be mounted in the panel board clips commonly provided for the reception of conventional fuses;

Fig. 15 is an end view largely in elevation and partly in section which may be regarded as taken on the line 15—15 of Fig. 14 and looking in the direction indicated by the arrows.

Similar characters of reference refer to similar parts throughout the several views.

In the foregoing synopsis of what the drawings depict, and in the description to follow, the terms "top," "bottom," "side," and "end" have been used for convenience on the theory that my novel circuit breaker is or is to be mounted on a horizontally disposed surface of a panel board or other support. However, it will be understood that a surface whereon is mounted one or more of my novel circuit breakers may be vertically rather than horizontally disposed or may be disposed at any required or preferred angularity to the vertical or the horizontal.

The thermostatic circuit breaker of my invention preferably comprises a closed housing 25 consisting of three components, namely, two desirably symmetrical metal side units 26 and 27 and the insulator unit 28.

Each of the metal side units 26 and 27 comprises a rectangularly dished central portion 29 having a marginal flange 30 provided with a plurality of notches 31 and a plurality of lugs 32, the notches being substantially wider than the lugs.

The marginal flange 30 of each metal side unit 26 and 27 desirably has a widened lower portion 33 which is slit at 34 and conformed to be concavo-convex beneath such slit 34, as indicated at 35, to provide an interiorly concave seat for the cylindrically convex surface 36 of the partially cylindrical upper end 37 of a desirably one-piece metal terminal. Such terminal suitably also

comprises a threaded shank 38, a disc-like portion 39 from which shank 38 projects downwardly and from which partially cylindrical upper end

37 projects upwardly, and a lip 40 formed on the upper extremity of upper end 37. Such partially cylindrical upper end 37 is formed with a plane surface 41 which lies coplanar with the adjacent plane inner surface of the flange portion 33 when the terminal is appropriately assembled with a metal side unit 26 or 27 as the case may be. Each of the one-piece terminals desirably is brazed to its associated side unit 26 or 27, with the terminal lip occupying the slit 34 of the side unit, with the cylindrically convex surface 36 of the terminal upper end 37 engaging the cylindrically concave surface of the side unit flange portion 33, and with the disc-like portion 39 of the terminal disposed in immediate contiguity to the lower edge of the widened portion 33 of the side unit flange 30. See Figs. 10 and 11.

Insulator unit 28 preferably consists of a single piece of fibre or other dielectric material having a rectangular central opening 42 and perimetrical notches 43.

As is most clearly shown in Figs. 1, 10 and 12, the dished portion 29 of housing side unit 26 is provided near one end thereof with an aperture in which is press-fitted and brazed one reduced end of a metal stud 44 which lies interiorly of the dished portion of the side unit 26 and is provided with a blind bore 45 opening exteriorly of the side unit 26. Such stud 44 is provided with another reduced end which extends through an aperture 46 in one end of a thermostatic reed 47 and conveniently is upset to secure such reed to the stud. To the reed 47, near the other end thereof, a suitable electrical contact 48 is riveted or otherwise secured. Reed 47 suitably is formed of commercial bi-metallic sheet or strip and desirably is processed, as hereinafter described, to accord it the optimum snap action requisite in a circuit breaker of my invention.

As is most clearly depicted in Figs. 8, 11 and 12, a second electrical contact 49, for cooperation with reed-carried contact 48 is suitably secured, as by riveting, to, within and near one end of the dished portion 29 of housing side unit 27.

With the contact-carrying thermostatic reed 47 assembled with housing side unit 26 as depicted in Fig. 7, and with contact 49 assembled with thermostatic side unit 27 as depicted in Fig. 8, the marginal flanges 30-30 of the two housing side units 26 and 27 are brought respectively into contact with and secured to the insulator unit 28 in such manner as to provide an effectively closed circuit breaker housing without permitting any flow of electricity from one to the other of the housing side units, except through the thermostatic reed 47 when the contacts 48 and 49 are in their normal or closed positions. It will be noted that each lug 32 of each housing side unit 26 and 27 projects through a notch 43 in the insulator unit 28 without contacting the other side unit 26 or 27, and is turned against the opposite face of the insulator unit where that face lies exposed by one of the notches 31 of the other side unit.

With the several elements of the circuit breaker thus assembled, the aperture 42 of the insulator unit 28 permits the thermostatic reed 47 carried by the housing side unit 26 normally to hold its contact 48 in engagement with the stationary contact 49 carried by the housing side unit 27.

Circuit breakers of my invention afford the very important advantage that a multiplicity of them may be mounted, with very economical use of space, upon and respectively edgewise to a common panel board, such as the one depicted at

50 in Fig. 13, through which the threaded shanks 33-38 of the circuit breaker terminals extend for cooperation with suitable nuts whereby the disc-like portions 39-39 of the terminals are drawn 5 snugly against the contiguous surface of the panel board and whereby the terminal shanks are held in electrical contact with conductors forming parts of the several circuits in and for the protection of which the circuit breakers are included. I believe I am the first to provide circuit breakers comprising thermostatic reeds which are carried and operate within wafer-like housings which are mountable edgewise to panel boards or equivalent supports whereon they are mounted.

The circuit breaker of Figs. 14 and 15 differs from that depicted in the preceding figures only with respect to the terminals with which the metal side units 26 and 27 of the housing are provided. Instead of being equipped with a brazed-on terminal having a threaded shank, each of the metal side units 26 and 27 of the circuit breaker of Figs. 14 and 15 is provided near one end of its lower edge with a rather long integral lug which is curvedly return-bent to form an open loop 51 which does not contact the other metal side unit. These loops 51-51 constitute terminals well suited for cooperation with panel board spring jaws such as are customarily provided to receive the cylindrical terminals of conventional fuses. At 52 in Figs. 14 and 15 is depicted a well-known type of panel board equipped with spring jaws 53-53 of the kind to which I have alluded. It will be noted that each of the loops 51-51 has an angularly turned extremity 51A adapted to abut the opposed angularly turned extremity 53a of the contiguous spring jaw 53. The cooperation of the spring jaw extremities 53a-53a and the terminal loop extremities 51A-51A effectively prevents the housing 25 from rocking in the spring jaws 53-53 to contact the housing of an adjacent circuit breaker.

As shown in Fig. 7, the thermostatic reed 47 preferably is processed so as to be provided with 45 a plurality of dimples 54. The dimples accord the reed optimum snap action when heated to a predetermined temperature as the consequence of an electrical overload, caused by a short or otherwise, of the circuit protected by the circuit breaker.

After the reed has been processed as just described, the contact to be carried with it is applied and the reed is assembled with the circuit breaker side unit 26, by being mounted upon the 55 stud 44 thereof as hereinbefore explained.

Usually, at least once, after one of my novel circuit breakers has been completely assembled it is tested for its ability effectively to open a circuit which it controls when that circuit carries 60 a predetermined overload for a significant or predetermined time interval. When such testing indicates, as it frequently does, that some adjustment of the circuit breaker is necessary or desirable, that adjustment almost invariably can be satisfactorily effected by inserting an adjustment tool, indicated in Fig. 12, in the blind bore 45 of the reed mounting stud 44 and then smoothly but firmly inclining the stud axis more or less in the medial horizontal plane of the housing 25, to vary the pressure with which the reed-carried-contact 48 normally engages the stationary contact 49. Moreover, such blind bore 45 of the stud 44 frequently is useful in effecting adjustments made before the several parts of the circuit breaker are completely assembled.

When one of my novel circuit breakers is in service, its thermostatic reed 47 snaps the movable contact 48 out of engagement with and substantially away from the stationary contact 49 when the reed becomes heated in consequence of a circuit protected by the circuit breaker carrying a certain predetermined overload, or greater overload, for a significant time interval. Unless conventional or other suitable means (not shown) are provided for preventing re-engagement of the contacts, the reed later snaps the movable contact 48 back into engagement with the stationary contact 49 pursuant to cooling of the reed. Whether the contacts are again more or less promptly separated by the reed 47 then depends upon whether the "short" or other cause of the overloaded condition of the protected circuit has been eliminated or substantially alleviated.

While I prefer that the reed 47 be heated as the result of its own resistance to current flowing through it from one to the other of the circuit breaker terminals, I realize, as will all skilled in the art to which my invention relates, that the heat whereto the thermostatic reed responds may be created in a contiguous conductor through which current flows from one to the other of the circuit breaker terminals.

My hereinbefore described circuit breakers, which can be very economically manufactured, are of sturdy construction, satisfactorily closed against the intrusion of ambient dust and moisture, and are dependable and effective in operation. Moreover, unlike fuses, they do not terminate their own usefulness when they have functioned to open circuits protected thereby. In bus and airplane and other automotive vehicle services, in which my new circuit breakers presently are being extensively used, their ability indefinitely to open and close an overloaded essential circuit oftentimes is of great practical advantage, because permitting the vehicle to reach its destination or a service station as would not be feasible if the overloaded essential circuit were fuse-protected.

Having thus illustrated and described my invention in presently preferred and commercially practical embodiments thereof, what I claim as new and desire to secure by Letters Patent of the United States is:

1. In a thermostatic circuit breaker, a housing core in the form of a flat continuous rim of dielectric material circumscribing an opening of substantially the same size and shape as the dished central portions of the hereinafter mentioned housing sides, a pair of symmetrical housing sides each in the form of a sheet metal member that is centrally dished away from said housing core and has a flat perimetrical flange between which and the corresponding flange of the other housing side the housing core is disposed and clamped, a thermostatic reed disposed within the housing and supported by and electrically connected with one of the housing sides, a stationary contact within the housing and supported by and electrically connected with the other of the housing sides, and spaced-apart lugs projecting from each of the aforesaid flanges of the housing sides and extending over adjacent edge portions of the housing core, each said lug bearing against that face of the housing core which lies away from the flange from whence the lug projects, the free end of each said lug of each of said flanges occupying a cove recess in but not contacting the other of said flanges.

2. A thermostatic circuit breaker according to claim 1 wherein the housing core is provided with a perimetrical notch snugly receiving each of the lugs of the flanges of the housing sides.
- 5 3. In a thermostatic circuit breaker, a substantially closed housing comprising a metal side wall portion, a stationary contact within the housing, a movable contact within the housing, a thermostatic reed also within the housing and carrying said movable contact at one of its ends, and an adjustable mounting, for the other end of said reed, which lies for the most part within said housing, said adjustable mounting consisting of a metal stud having two reduced ends, one of said reduced ends being received by and retained in an aperture afforded by the reed, the other of said reduced ends being received by and extending through and secured in an aperture afforded by the aforesaid metal side wall portion of the housing and presenting an axial bore of substantial depth opening exteriorly of the housing and having a blind end located intermediate the reduced ends of said stud.
- 10 4. In a thermostatic circuit breaker, a substantially closed housing comprising a metal side wall portion, a stationary contact within the housing, a movable contact within the housing, a thermostatic reed also within the housing and carrying said movable contact at one of its ends, and an adjustable mounting for the other end of said reed, said mounting lying largely within the housing and not extending exteriorly thereof, said mounting consisting of a metal stud having one end thereof secured to said reed and its other end reduced and received by and extending through and brazed in an aperture afforded by the aforesaid metal side wall portion of the housing, said last mentioned end of the stud presenting an axial blind bore of substantial depth opening exteriorly of the housing.
- 15 5. In a thermostatic circuit breaker, a housing core in the form of a flat continuous rim of dielectric material circumscribing an opening of substantially the same size and shape as the dished central portions of the hereinafter mentioned housing sides, a pair of symmetrical housing sides each in the form of a sheet metal member that is centrally dished away from said housing core and has a flat perimetrical flange between which and the corresponding flange of the other housing side the housing core is disposed and clamped, a thermostatic reed disposed within the housing and supported by and electrically connected with one of the housing sides, a stationary contact within the housing and supported by and electrically connected with the other of the housing sides, devices for retaining the housing core clamped between the flat perimetrical flanges of the housing sides without electrically connecting said sides, each of said perimetrical flanges being provided with a concavo-convex portion affording a cylindrically concave seat that is presented toward the housing core and extends crosswise of the flange to the perimetrical edge thereof, and a pair of elongated metal terminal members each presenting at one end thereof a cylindrically convex surface and a plane surface, the aforesaid cylindrically convex surface of each terminal member being disposed and secured in one of the aforesaid cylindrically concave surfaces, and the aforesaid plane surface of each terminal member being flush with that face of its associated flange that is presented to the housing core.
- 20 6. In a thermostatic circuit breaker, a housing

core in the form of a flat continuous rim of dielectric material circumscribing an opening of substantially the same size and shape as the dished central portions of the hereinafter mentioned housing sides, a pair of symmetrical housing sides each in the form of a sheet metal member that is centrally dished away from said housing core and has a flat perimetrical flange between which and the corresponding flange of the other housing side the housing core is disposed and clamped, a thermostatic reed disposed within the housing and supported by and electrically connected with one of the housing sides, a stationary contact within the housing and supported by and electrically connected with the other of the housing sides, devices for retaining the housing core clamped between the flat perimetrical flanges of the housing sides without electrically connecting said sides, and a terminal carried by the perimetrical flange of each of the housing sides, each said terminal being a lug that is integral with its associated flange and extends laterally therefrom and is curvedly rebent for cooperation with fuse-engageable spring clips presented by a panel board or the like.

7. A thermostatic circuit breaker according to claim 6 wherein each of the curvedly rebent terminal lugs is provided with an angularly turned extremity for cooperation with a spring clip extremity to prevent turning of the terminals in the spring clips.

8. In a thermostatic circuit breaker, a pair of metallic members positioned in spaced opposed relation, a ring of dielectric material clamped between the margins of the metallic members to maintain their spacing and to form therewith a housing, a thermostatic element positioned within

the ring and between the members in generally parallel spaced relation to the latter, means electrically connecting to and supporting the element on one metallic member, and a contact carried by the other metallic member for engagement with the element, the supporting means for the thermostatic element comprising a metallic stud having one end connected to the element and the other end connected at a recess in the said one member and provided with a blind axial bore of substantial depth opening exteriorly of the said one member.
